UNITED STATES PATENT OFFICE.

CHARLES A. MEEKINS, OF NEW HARTFORD, CONNECTICUT.

BENCH-PLANE.

SPECIFICATION forming part of Letters Patent No. 295,414, dated March 18, 1884.

Application filed May 31, 1883. (No model.)

To all whom it may concern:

Be it known that I, CHARLES A. MEEKINS, of New Hartford, in the county of Litchfield and State of Connecticut, have invented a certain new and useful Improvement in Bench-Planes, of which the following is a description, reference being had to the accompanying drawings, where—

Figure 1 is a side view, with a portion of the sides of the stock represented as broken away. Fig. 2 is a view looking diagonally down upon the top from the point a^5 over Fig. 1. Fig. 3 is a view of the plane in central vertical lengthwise section. Fig. 4 shows a detail top view 15 of the rocking clamp-iron, and also a detail side view of the same.

The letter a denotes the stock or body of the plane, which may be partly of wood and partly of metal, or substantially wholly of 20 wood or wholly of metal. In the drawings I show it with the bottom part composed of wood and the upper part of iron.

The letter b denotes the chisel or plane-iron, of the ordinary kind. The letter c denotes 25 the cap-iron, which is novel in its construction; but it is secured to the plane-iron b , in substantially the ordinary way, by the connecting-screw d .

The letter e denotes what I call the "rocking clamp-iron," because it has a rocking motion for effecting the adjustment of the plane-iron and cap-iron on the studs or pivots $a' a'$; and it also serves in a novel manner the function of a clamp-iron—that is, it is the important factor in attaching the plane-iron and 30 the cap-iron to the stock of the plane. This rocking clamp-iron runs under the cap-iron. The pin e' , jointed somewhat loosely at the bottom to the rocking clamp-iron, projects up 35

through the cap-iron, and upon the upper end bears the nut f , by means of which the plane-iron and cap-iron are clamped to the stock—that is, by running the nut down, the journal ends of the rocking clamp-iron press against the studs $a' a'$, and the plane-iron is forced firmly down upon its seat. This rocking clamp-iron has an extended part or lever end, e'' , the end of which is bifurcated, and takes hold of an annular groove in the adjusting-screw g , which is hung in the cap-iron. 40 By manipulating this adjusting-screw the edge of the plane-iron may be nicely adjusted. The mode or manner in which this is effected is not, perhaps, plain at a first glance; but the explanation is that by manipulating this adjusting-screw the clamp-iron is rocked on pivots a' , and carries the plane and cap irons with it in its up and down but not its rocking movements. 45

I claim as my improvement—

1. In combination, the plane-body bearing the pivots, the plane-iron, the cap-iron attached to the plane-iron, the longitudinally-rocking clamp-iron, adjustably connected to the cap-iron and bearing between its points of connection upon the pivots on the plane-body, all substantially as described. 50

2. The combination of the longitudinally-rocking clamp-iron e , loosely attached to cap-iron c by pin e' and nut f , adjusting-screw g , 55 plane-iron b , and plane-body a , with pivot-bearings for the clamp-iron, all substantially as described. 60
